Primary Examiner — Mojtaba Tehrani(74) *Attorney, Agent, or Firm* — BRANNEN LAW OFFICE, LLC(57) **CLAIM**

The ornamental design for a stock framework, as shown and described.

DESCRIPTION

FIG. 1 is a right side view of a stock framework, showing my new design;

FIG. 2 is a top, front, right side perspective view thereof;

FIG. 3 is a bottom, rear, left side perspective view thereof;

FIG. 4 is a right side view thereof;

FIG. 5 is a left side view thereof;

FIG. 6 is a front view thereof;

FIG. 7 is a rear view thereof;

FIG. 8 is a top view thereof; and,

FIG. 9 is a bottom view thereof.

The broken lines shown in the drawings are for environmental purposes only and form no part of the claimed design.

1 Claim, 5 Drawing Sheets(56)
